HERMANN SUNDHAUSSEN, OF ESSEN-ON-THE-RUHR, GERMANY, ASSIGNOR TO FRIED.
KRUPP AKTIENGESELLSCHAFT, OF ESSEN-ON-THE-RUHR, GERMANY.

AUTOMATIC ELECTROMAGNETIC SWITCH.

Application filed March 31, 1921. Serial No. 457,315.

To all whom it may concern:

Be it known that I, HERMANN SUNDHAUSSEN, residing at Essen-on-the-Ruhr, Germany, a citizen of the German Republic, have 5 invented a certain new and useful Improvement in Automatic Electromagnetic Switches, of which the following is a specification.

The present invention relates to an automatic electromagnetic switch, in which the armature of an electromagnet is transferred by its tractive force from a position of readiness, which enables a locking device to intercept a releasing device, into an operative position which bridges over a gap in the circuit to be closed, as soon as the releasing device touches the locking device.

A constructional example of the subject matter of the invention is diagrammatically 20 shown in the drawing in which:

Figure 1 is a view of the switch in its switched out position.

Figures 2 and 3 are each views corresponding to Figure 1 with certain parts in a different position.

The electromagnetic switch contains two contacts a^1 and b^1 , which are placed in a circuit to be closed by the switch. One of the contacts, a^1 , is mounted on a member 30 a^2 which is fixed to the core A of an electromagnet provided with an exciting winding a^3 and insulated therefrom. The other contact, b^1 , is mounted on and insulated from one end of a two-armed lever B B^2 which forms the armature of the electromagnet and is pivotally mounted on the core A by the aid of a pin a^4 . The arm B of the lever B B^2 is provided with a rib 35 b^3 , through which the lines of force pass over between the core A and the armature B B^2 when the electromagnet is working. The two-armed lever B B^2 is under the action of a spring C, which is attached by one end to the core A and by the other end 40 to the lever arm B B^2 and tends to rotate the lever B B^2 in the direction of the arrow x . On the free end of the lever arm B B^2 is pivotally mounted by means of a pin b^4 a locking device D. One end of this locking device 45 D is constructed in the form of a tongue d^1 and is intended to cooperate with a releasing device E of an electromagnetic apparatus which serves to release the locking device D. The releasing device E which 50 is acted on by a spring e^1 carries the arma-

ture e^3 of a small electromagnet, the core e^4 of which is stationary. At the upper end of the locking device D is mounted a lug d^2 which places itself on a stop a^5 mounted on the core A, when the two-armed lever 60 B B^2 rotates in the opposite direction to that of the arrow x . The locking device D is acted on by a spring F, one end of which is attached to the lever arm B B^2 and the other end to the locking device D and tends 65 to rotate it in the direction of the arrow y .

Supposing the circuit containing the contacts a^1 and b^1 is to be closed by the above described switch, the exciting winding a^3 is first energized. The armature formed 70 by the two-armed lever B B^2 therefore begins to rotate under the action of the tractive force of the electro-magnet about the pin a^4 in the opposite direction to that of the arrow x . During this rotation the two-armed lever B B^2 moves out of its position of rest shown in Figure 1 into an intermediate position shown in Figure 2, in which the locking device D places itself with its lug d^2 on the stop a^5 and thereby prevents 75 any further rotation of the two-armed lever B B^2 . By the hitherto described rotation of the two-armed lever B B^2 the locking device D (see Figures 1 and 2) is lowered to such an extent that now the tongue d^1 , 80 which was previously in a position of rest outside the path of the releasing device E, assumes a position, in which it lies in the path of the releasing device E. The above mentioned intermediate position of the lever B B^2 therefore constitutes a position of 85 readiness. If during this position of the parts the exciting winding belonging to the electromagnet e^3 e^4 be transitorily energized say by the swing of a pendulum (not shown) for example, the releasing device E rotates under the action of the tractive force of this electro-magnet in a clockwise direction in opposition to the action of the spring e^1 and thereby strikes against 90 the tongue d^1 of the locking device D. As soon as this is the case the locking device D is rotated against the action of the spring F. During this rotation the lug d^2 slides 95 from its seat a^5 and thereby releases the lever B B^2 . As soon as this happens, the lever B B^2 is rotated further by the electromagnet in the opposite direction to that of the arrow y . The rotation takes place 100 with very great rapidity, as the tractive 105

lever B B^2 is rotated further by the electromagnet in the opposite direction to that of the arrow y . The rotation takes place 110 with very great rapidity, as the tractive

force of the electro-magnet with the considerably smaller air gap between the rib b^3 of the armature B B² and the core A is much greater than before, and the contacts 5 b^1 and a^1 pass accordingly very quickly into contact with each other (Figure 3). The lever B B² now assumes its operative position, in which by the contact of the contacts a^1 and b^1 the circuit to be closed is 10 closed. As at the instant of touching of the contacts a^1 and b^1 and for the further duration of the excitation of the winding a^3 the tractive force of the electro-magnet is a multiple of its initial value, the contact of the 15 two contacts b^1 and a^1 is assured, although the contact b^1 has struck with great rapidity the stationary contact a^1 by the very rapid rotation of the two-armed lever B B². The circuit containing the contacts a^1 and b^1 is 20 therefore rapidly closed and without any brief interruption of the first closing of the circuit.

Supposing the circuit containing the contacts b^1 and a^1 is to be broken again, the 25 exciting winding a^3 is cut off from its source of current (not shown). The exciting winding a^3 will accordingly be de-energized, and the electro-magnet A loses its power of attraction. The armature B B² 30 will therefore be rotated by the spring C out of the operative position shown in Figure 3 in the direction of the arrow α until it assumes again the position of rest illustrated in Figure 1. Further the locking 35 device D will also be brought during the last mentioned rotation of the double lever B B² after sliding past the stop a^5 back into the angular position with relation to the lever arm B² under the action of the 40 spring F. As furthermore the electro-magnet e^4 , which was only temporarily energized, has also lost its tractive force again, the releasing device E has also returned under the action of the spring e^1 into the 45 angular position shown in Figure 1 and all the parts therefore again take up the position from which the description of the action of the apparatus was commenced.

In the switch which forms the subject 50 matter of the present invention the movement of a single member (the double lever B B²) produces both the bringing up of the locking device D into its position of readiness and also effects the closing of the circuit to be closed. This ensures for the electro-magnetic switch here in question a particularly simple and accessible construction and enables consequently to obtain a very fine adjustment and great reliability of action of the switch. A further important 55 advantage of the subject matter of the invention follows from the fact that the force which tends to effect the touching of the two contacts increases very rapidly as the 60 two contacts approach each other and that

this force, at the instant at which they touch, is a multiple of its initial value. By this increase of the force tending to effect the touching of the two contacts the movable contact is prevented from jumping 70 back or rebounding one or more times after it has first touched the stationary contact. The prevention of the aforesaid rebound ensures however that the current flowing through the contacts suffers no interruption by such rebound and its increase is therefore dependent only on the electrical magnitudes which control it i. e. voltage and resistance of the circuit. Automatic electromagnetic switches with the 80 above mentioned advantages are of particular importance where for example it is required to energize by means of an automatic switch the winding of a relay the (previously determined) delay of which must not 85 suffer any change whatever.

A particularly suitable automatic switch is provided if the movable contact b^1 be resiliently mounted on its carrier which is 90 formed by the lever arm B, as by this means the wear of the contacts which strike against each other with great rapidity is considerably reduced.

Claims.

1. An automatic electromagnetic switch 95 comprising a fixed and a movable switch element, an electromagnet, an armature for said electromagnet pivotally mounted and influenced by said electromagnet, said armature carrying said movable switch element, a locking device for holding said armature in open circuit position, said locking device embodying a locking lever pivotally secured to said armature and a releasing device for displacing said locking arm, 100 said locking arm being situated in the path of said releasing device when said armature is in its open circuit latched position. 105

2. An automatic electromagnetic switch comprising an electromagnet, a double 110 armed lever pivoted thereto and forming the armature of said electromagnet, a contact carried by one end of said double armed lever and adapted to engage a stationary contact for completing the circuit to be closed, a locking device for said double armed lever for holding said lever in open circuit position, said locking device including an arm pivoted to the other end of said double armed lever and a releasing device 115 for displacing said last mentioned arm, said last mentioned arm being situated in the path of said releasing device when said double armed lever assumes its open circuit latched position. 120

3. An automatic electromagnetic switch comprising an electromagnet, a double armed lever pivoted thereto and forming the armature of said electromagnet, a contact carried by one end of said double 125 130

armed lever and a contact carried by said electromagnet and adapted upon engagement to complete the circuit to be closed, a locking device for holding said double armed lever in open circuit position, said locking device including an arm pivotally mounted upon the other end of said double armed lever, a stop carried by said electromagnet and adapted to be engaged by a lug 5 carried by said arm and means tending to rotate said arm to cause said lever to engage said stop and a releasing device for rotating said arm against the action of said last mentioned means to release said locking device, said arm being situated in the path of said releasing means when said double armed lever assumes its open circuit latched position.

4. An electromagnetic switch comprising an electromagnet, a double armed lever secured thereto and forming the armature of said electromagnet, switch contacts carried by said magnet and one end of said double 10 armed lever respectively for completing the circuit to be closed, a locking device for intercepting the movement of said double armed lever and retaining the same in open circuit position, said locking device embodying a stop carried by said electromagnet, an arm pivotally secured to the other end of 15 said double armed lever, said arm being formed with a catch for engaging said stop, spring means tending to rotate said arm to a position whereby said catch will engage said stop and an electrically operated releasing device for swinging said arm against the action of said spring means for disengaging said locking device, said arm being situated in the path of said releasing device when said double armed lever 20 assumes its open circuit latched position.

The foregoing specification signed at Essen, Germany, this 7th day of February, 1921.

HERMANN SUNDHAUSSEN.
